UNITED STATES PATENT OFFICE.

SAMUEL R. BACHTEL, OF LAFAYETTE, INDIANA, ASSIGNOR TO THOMAS DUNCAN, OF LAFAYETTE, INDIANA.

FAN.

SPECIFICATION forming part of Letters Patent No. 769,676, dated September 6, 1904.

Application filed October 28, 1901. Serial No. 80,245. (No model.)

To all whom it may concern:

Be it known that I, SAMUEL R. BACHTEL, a citizen of the United States, residing at Lafayette, in the county of Tippecanoe and State 5 of Indiana, have invented a certain new and useful Improvement in Fans, (Case No. 1,) of which the following is a full, clear, concise, and exact description, reference being had to the accompanying drawings, forming a part of 10 this specification.

My invention relates to fan-motors, and has for its object the provision of an improved motor construction by means of which the rotating fan portion thereof is adapted to cause either a rotary motion of the fan-support 15 about an axis or to change the direction of rotation intermittently, thereby causing an oscillatory movement of said fan-support, whereby it is possible to spread the effect of 20 the air-blast emanating from the fan throughout an angular space which may be varied from zero to three hundred and sixty degrees.

In the preferred form of my invention the air-blast emanating from the fan causes oscillatory movement of the fan-support, by virtue 25 of which construction I am enabled to produce a most effective distribution of the air-blast.

My invention further contemplates improved means whereby the fan-axis is given a varied angular position with respect to the vertical axis about which the support is rotatable, my improved construction contemplating additional means whereby the direction 35 of the angular position with respect to the axis of the support may be reversed at will, so that the direction of rotation of the support may be changed, if desired.

My invention also has for its object a general improved construction for motors of this type, as will be hereinafter more specifically set forth.

I will describe one embodiment of my invention as applied particularly to an electrically-driven fan by reference to the accompanying drawings, in which—

Figure 1 is a side view, partly in section, of a fan-motor constructed in accordance with my invention. Fig. 2 is a sectional view on

line *a a* of Fig. 1. Fig. 3 is a detail view of 50 the controlling mechanism. Fig. 4 is a detail sectional view of a brush-holder. Fig. 5 is a top view of the brush-holder shown in Fig. 4.

Like characters of reference indicate like parts throughout the different figures. 55

Referring now particularly to Fig. 1, I have shown a pedestal 1, upon which my improved fan-motor may be mounted, said pedestal pivotally supporting a motor-containing casing 2, which is constructed, preferably, in 60 two parts and secured together by means of bolts 3. Any rotating or oscillating mounting 2 for the fan will satisfy many embodiments of my invention.

The manner of pivotally mounting the motor and fan supporting frame 2 upon the pedestal 1 preferably comprises two steel washers 4, which are provided with grooves adapted to receive steel balls 5, the two washers, together with the interposed balls, being mounted 70 on the top of the pedestal 1. The casing 2 has a hollow extension or neck 6, about which said steel washers 4 are adapted to loosely fit, the removal of said washers from the said neck being prevented by means of a 75 collar 7, sprung into a groove about the neck 6. The washers 4 are held in place upon the pedestal 1 by means of a collar 8, which has threaded engagement with said pedestal. By means of this construction the casing 2 80 may revolve about its vertical axis while still retaining a secure and firm mounting therefor, as the collar 7 prevents the casing from being withdrawn through the washers 4, while the said washers are held in place upon 85 the pedestal 1 by means of the collar 8. A hard-rubber bushing 9 is fitted tightly into the neck 6 and serves both as an insulating-sleeve through which the lead-wires to the motor in the motor-casing may be passed, as 90 well as providing a suitable mounting for two collector-rings 10, with which said lead-wires are adapted to be connected.

Current is supplied to the collector-rings 10 10 by means of brushes 11 12, suitably 95 mounted upon a hollow standard 13, secure within the pedestal 1 by means of a fibre block 14. The standard 13 is provided with

resistance-coils connected to buttons 15, suitably secured upon the fiber block 14, one terminal of the said resistance being connected directly with the brush 11. The remaining 5 brush 12 is adapted for connection with an electric circuit, the remaining terminal of the electric supply-circuit being connected to an arm 16, pivotally mounted upon the block 14, which arm is adapted to engage the contact- 10 buttons 15, having connection with the resistance-coils provided in the standard 13, thereby to effect a change of speed in the operation of the driving-motor. The collector-rings 10 10 supply current conducted to them 15 to brushes 17 17, which engage a commutator 18, electrically connected with the armature 19 of a motor. One of the field-coils 20 of the motor is shown mounted upon a core 21, which is held in place in the casing 2 by 20 means of ledges or lugs 22, formed upon the inside of said casing, sufficient pressure being exerted by means of the bolts 3. The armature and field-coils are preferably connected in series, so that all the current passes 25 through the brushes 17.

The armature 19 is mounted upon a shaft 23, which is revoluble in suitable bearings provided in the casing 2. The power developed by the motor is transferred to the fan-blades 30 by means of a flexible shaft 24, this flexible shaft being connected to a shaft 25, provided with a suitable spider 26 for supporting the fan-blades 27. The shaft 25 is mounted within an 35 adjustable shell or support 29. The shell 29 also carries a guard 30, which surrounds the fan-blades 27. The adjustable shell 29 is provided with a spherical end, which is clamped into the spherical socket provided in a revolving 40 sleeve or bearing 31 by means of a nut 32. The axis of the bearing 31 is preferably coincident with the axis of the motor. The fan-blades, together with their guard 30, may thus be adjusted to any desirable angle with 45 respect to the vertical axis about which the casing 2 may be revolved, so that if power is supplied to the motor and the fan-blades actuated by reason of the angular displacement of the shaft 25 a bodily movement of the fan- 50 blades, together with the whole supporting-casing 2, will be caused in the direction of the arrow shown in Fig. 2.

The revolving sleeve 31, upon which the guard 30 and the fan-blades are supported, 55 is rotatably mounted within a circular aperture provided in the casing 2, said circular aperture having an annular groove 33 adapted to receive steel balls 34, which steel balls are adapted to act as bearing-surfaces for said 60 revolving sleeve 31, a collar 35 being secured to said revolving sleeve and also engaging said steel balls 34, whereby the said revolving sleeve is held in position and may be readily revolved about an axis, in this particular instance coinciding with the axis of

the armature of the motor. The revolving sleeve 31 would with the construction so far described revolve, together with the fan-blades and the guard 30, about its axis in a direction corresponding to the direction of 70 the rotating shaft of the motor, due to the friction of the shaft 25 in its bearing 28.

In order to hold the revolving casing normally in a position of rest, a lug 36 is provided upon the interior periphery of said sleeve, which lug is adapted to be engaged by either of the arms 37 37 of an escapement 38, which escapement is pivotally mounted in a bearing 39, provided upon the casing 2. As is apparent from Fig. 2, the lug 36 prevents the sleeve from rotating in the direction of the shaft, as the said lug engages one arm 37 of the escapement 38. The escapement 38 is provided with an angular extension 40, which is adapted to engage fixedly-secured detents 41 41, mounted upon collars 42, held in place upon the pedestal 1. An engagement of the angular extension 40 with either detent 41 will shift the position of the escapement 38 so as to release the arm 90 which had hitherto been in association with the lug 36 and places the remaining arm in a position to prevent a movement of said sleeve when said lug comes in contact therewith, thus permitting of a periodic angular movement of the said sleeve about its axis. 95

The improved means which I employ for adjustably mounting the brushes 17 consists in a supporting insulating-bushing 43, secured to the casing 2, which bushing serves to hold 100 a supporting-annulus 44 by means of a nut 45, having screw-threaded engagement with said annulus 44. The lead-wires are also adapted to be secured in place and have electrical connection with said annulus 44 through 105 the agency of the nut 45, acting in association with the bushing 43. A plunger 46 travels within the annulus 44, said plunger having a pin 47 adapted to slide within a slot 48, provided in said annulus, whereby a rotation of 110 said plunger relative to the said annulus is prevented. The plunger is thus adapted for longitudinal movement within said annulus, so that a perfect engagement between the brushes 17 and the commutator may be effected. 115 A spring 49, acting against said plunger, serves to push the brush against the commutator, the tension of said spring being regulated by means of a nut 50, having screw-threaded engagement with the annulus 44. 120

The manner in which I secure the advantages obtained by my device will now be apparent. The ball-and-socket joint comprising the spherical-shaped end 29 of the fan-blade support is fastened in its support by 125 means of the nut 22 in such manner that the axis of rotation of the fan-blades is placed diagonally with respect to the central axis about which the casing 2 is rotatable. The casing 2, which is rotatable by means of the 130

steel balls 5, may thus be revolved when the fan-blades are started. When current is supplied to the motor through the collector-rings 10 10, the motor is caused to revolve, thereby 5 rotating the flexible shaft 24 and the shaft upon which the fan-blades 27 are mounted. The consequent rotation of the fan-blades exerts a force in heating the air that tends to rotate the casing 2, which rotation would be 10 completed through three hundred and sixty degrees if nothing intervened to prevent such motion. In some embodiments of my invention such complete circular motion will be of advantage; but to adapt the same for use in 15 confined areas where the agitation need not be spread over such a large arc I provide means in connection with the rotating fan-blades by means of which their position is so changed that upon reaching a limiting position they will rotate the casing back to its starting-point. This is accomplished, as before stated, whenever the escapement 38 is pushed against either one of the detents 41, the position of which detents may be regulated 20 as desired.

Referring more particularly to Fig. 3, the rotatably-mounted escapement 38 is shown as about to strike a detent 41, whereupon the said escapement 38 will be rotated out of engagement with the lug 36, whereby it is then possible for the rotating shaft 25, due to the friction thereof in its bearing, to rotate the whole rotatably-mounted support for the fan-blades about its axis, due to the steel balls 34 30 upon which the same is mounted. The fan-blades, together with their support, will revolve through an arc of approximately one hundred and eighty degrees or until the lug 36 engages the other arm 37 of the escapement 38. 35 The whole rotatable support comprising the fan-blades, together with their shaft and the guard, has now come to rest in a position which is angularly displaced from the axis about which the casing 2 is rotatable, but on the opposite side to the one on which it had been previously displaced, then occupying the general position indicated by the dot-and-dash line. In this position the rotating fan-blades have a tendency to rotate the casing 2 in a direction opposite to the one in which the said fan-blades previously served to rotate it, and a continued rotation of the fan-blades or fan after rotary movement of the sleeve 31 has ceased will 45 reverse the casing 2 back toward its original position—that is, in a direction opposite to the one in which it was rotating before the escapement 38 engaged the detent 41. The reverse rotation of the casing 1 now brings the escapement 38 toward the other detent 41. Upon 50 an engagement of the escapement with this second detent 41 the arm 37 which is at that particular time engaging the lug 36 is released from said engagement, and the rotatable sleeve 31 thereupon is permitted to rotate about its 55 axis, due to the mounting thereof upon the

steel balls 34, said rotation being caused by the friction of the shaft 25 in its bearing. The fan-blades, together with their support and the guard, upon a completion of the rotation of the rotating sleeve assume the position they originally occupied, whereby the axis of rotation of said fan-blades is again displaced to the first aforesaid side of the axis relative to the axis of the rotating sleeve 2. The rotation of the fan-blade support toward 70 its original position again places the lug 36 into engagement with the first aforesaid arm 37, and the continued rotation of the fan-blades again causes rotation of the casing 2 from its initial position. It will thus be seen that I 75 am enabled to provide an oscillatory motion for the fan-blade-supporting casing whereby the agitation of the atmosphere over a limited arc less than three hundred and sixty degrees may be secured. The size of the arc depends, 80 of course, upon the displacement of the detents 41, which detents actuate the controlling mechanism for reversing the direction of the angular displacement between the fan-blade axis and the axis of the rotating sleeve 2. 90

In the claims I have specified a fan as signifying the rotatable shaft, together with the fan-blades or its substantial equivalent, whereby a blast of air may be created due to the rotation thereof. It has been apparent 95 that the fan has, by means of the sleeve 31 and associated parts, provided for it a bearing that is angularly displaced with respect to the fan's axis of rotation and that the fan's axis is periodically movable from side to side 100 of the axis of this bearing. I have shown a specific means whereby the axis about which the prime mover is bodily rotatable is made transverse to the prime mover's own axis of rotation, which of course is the axis of the 105 armature. Other means may be employed, however. The flexible shaft 24 constitutes the preferred means for effecting driving connection between the prime mover or armature 19 and the fan, while the sleeve 31 constitutes the preferred form of rotatable mounting, bearing, or support for the fan to permit of periodic change of the fan's axis with respect to the axis of said sleeve. Other mechanism performing these functions may be employed, however, without departing from my invention; nor do I wish to be limited to the form of oscillating mounting 2 employed. I prefer the flexible shaft 24, constituting a bent shaft for the fan; but I do not wish to be 110 limited thereto in all embodiments of the invention.

By the term "oscillate" used herein with respect to the position of the fan's axis of rotation I mean a change in the position of the 115 fan's axis from side to side, which in the particular instance shown is accomplished by the intermittent rotation of the sleeve 31 in a uniform direction.

While I have herein shown and particularly 120

described one embodiment of my invention, it is obvious that changes and modifications may readily be made therein without departing from the spirit of my invention, and I do not, therefore, wish to be limited to the precise construction and arrangement herein shown nor to its operation by direct current; but,

Having thus described my invention, I claim

- 10 as new and desire to secure by Letters Patent—
  - 1. The combination with a rotatable fan, of a movable support 2 therefor, means for driving said fan, a rotating bearing 31 interposed between the fan and the said movable support, and means serving to reverse the angular disposition of the fan's axis relative to the axis of the rotatable support thereby serving to rotate said support in either direction, substantially as described.
  - 15 2. The combination with a fan, of a rotatable support 2 therefor, means for causing a rotation of said fan, said fan having its axis capable of angular displacement with reference to that of the rotatable support, and a rotating sleeve 31 interposed between the said fan and the said support for effecting a change in the direction of the angular displacement of the fan-axis relative to the axis of the rotatable support, substantially as described.
  - 20 3. The combination with a rotatable fan, of a rotatably-mounted support 2 for said fan, means for causing the rotation of said fan, a flexible shaft interposed between the said means and the said fan to drive the same and permit the change in the angular relation of the fan's axis and that of the support, a rotatably-mounted sleeve 31 interposed between the fan and the said support, and an escape-
    - 25 ment coöperating with the sleeve to effect change in the adjustment of the fan's axis, for effecting a change in the direction of the angular displacement of the fan's axis relative to the axis of the rotatable support, substantially as described.
  - 30 4. The combination with a rotatable fan, of

a rotatably-mounted support 2 for said fan, means for causing a rotation of said fan, a flexible shaft interposed between the said means and the said fan, a rotatably-mounted sleeve, 31, interposed between the said fan and the said support for effecting a change in the direction of the fan's axis relative to the axis of the rotatable casing, an adjustable support 29, interposed between said fan and said sleeve to change the angular position of the fan's axis, means for effecting a rotation of said sleeve-bearing by the fan, and means periodically to prevent the rotation of said sleeve, substantially as described.

5. The combination with a fan, of a rotatable support 2 therefor, means for driving said fan, a flexible shaft interposed between the said means and the said fan, a sleeve 31 rotatably mounted upon the said support, within which said fan is mounted, means whereby said fan is to cause a rotation of the said sleeve, an adjustable support interposed between said fan and said sleeve to change the angular position of the fan's axis, and means for preventing said fan from rotating said sleeve, substantially as described.

6. The combination with a fan, of a rotatable support 2 therefor, means for driving said fan, a flexible shaft interposed between the said means and the said fan, a sleeve 31 rotatably mounted upon the said support, within which said fan is mounted, automatic means for adjusting the angular position of the said fan relative to the said rotatable sleeve, means whereby said fan is adapted to cause a rotation of the said sleeve, and means for preventing said fan from rotating said sleeve, substantially as described.

In witness whereof I hereunto subscribe my name this 24th day of October, A. D. 1901. 85

SAMUEL R. BACHTEL.
